UNITED STATES PATENT OFFICE.

FLOYD L. LELAND, OF FLINT, MICHIGAN.

VACUUM-CLEANER.

1,352,520.

Specification of Letters Patent. Patented Sept. 14, 1920.

Application filed September 21, 1918. Serial No. 255,129.

To all whom it may concern:

Be it known that I, FLOYD L. LELAND, a citizen of the United States, residing at Flint, in the county of Genesee and State of Michigan, have invented certain new and useful Improvements in Vacuum - Cleaners, of which the following is a specification, reference being had to the accompanying drawings.

1.0 This invention relates to an improved vacuum cleaner, and has for its primary object to provide a hand operated cleaning device which will be efficient and serviceable in practical use, is light in weight so that 15 it may be readily manipulated or moved from place to place, and is operable with the expenditure of relatively little manual labor.

It is another and more particular object 20 of the invention to provide a cleaning device having a pole or handle and a suction fan mounted thereon including a casing, a dust collecting nozzle connected to the casing, a sack or receptacle into which the dust is 25 discharged, gearing for operating the fan, and manually operable means for actuating said gearing.

It is also another object of my invention 30 to provide a cleaning device as above characterized which is not liable to get out of order, and can be manufactured and sold at relatively small cost.

With the above and other objects in view, the invention consists in the improved construction, combination and relative arrangement 35 of the several parts as will be herein-after more fully described, subsequently claimed and illustrated in the accompanying drawing in which similar reference characters designate corresponding parts throughout the several views, and wherein:-

Figure 1 is a side elevation illustrating the preferred embodiment of the invention;

Fig. 2 is a longitudinal sectional view 45 through the gear casing; and

Fig. 3 is a section taken on the line 3-3 of Fig. 1.

Referring in detail to the drawing, 5 designates a tubular pole which may be of any desired length, and is preferably formed of sheet metal. One end of this pole is flattened and closed, and to the same at one side thereof, a longitudinally extending gear casing 6 is securely fixed. A bearing plate 55 7 is fixed at one of its ends to the opposite

side of the pole 5 and extends longitudinally along one side of the casing 6 and is fixed to the casing wall by means of the screws, indicated at 8.

To the casing 6, on one side thereof, a fan housing 9 is secured. 10 designates the fan shaft, which is suitably journaled in bearings provided upon the housing and casing walls, and to said shaft the radially extending fan blades 11 are fixed. 12 designates the induction tube, which is suitably connected to the annular wall of the housing 9 at one of its ends, and at its other end is provided with the collecting nozzle 13, which may be of any preferred construction. The annular wall of the fan housing is provided at the opposite side of the shaft 10 and below the pole 5, with an eduction nipple 14, through which the collected dust and dirt is discharged into a sack or receptacle 15 which is connected at one of its ends to the nipple 14 and at its other end is detachably connected to the pole 5, as shown at 16. One side wall of the housing 9 is provided with a slot or opening 17, preferably of substantially semi-circular form and located contiguous to the fan axis 10. Through this opening, air is drawn by suction in the rotation of the fan blades and an induced draft of air thereby created through the tube 12 and the nozzle 13.

Upon the fan shaft 10, and within the casing 6, a pinion 18 is secured. A relatively large gear 19 meshes with said pinion, the shaft 20 for said gear being journaled in the opposite side walls of the casing 6 and also having a pinion 21 fixed thereon. In the plate 7 and the opposite side wall of the casing 6, a shaft 22 is journaled and upon said shaft, a gear wheel 23 is fixed, said gear wheel meshing with the pinion 21. A crank arm 24 is fixed on one end of the shaft 22 exteriorly of the casing 6.

In the other end of the tubular pole 5, the shank of a curved handle or grip 25 is riveted or otherwise secured. This end of the pole is formed with an apertured lug or ear 26 in which the pin 27 is loosely mounted for rocking movement. To one end of this pin, a lever 28 is secured, while to the other end thereof, the arm 29 is fixed. This arm is of considerably greater length than the arm 24 fixed on the shaft 22, and a rod 30 operatively connects said arms to each other at their free ends. 31 designates a coil 32

spring which is suitably attached at one of its ends to the end of the arm 29 and has its other end attached to the pole 5.

In the operation of the device, the nozzle

- 5 13 is engaged upon the floor or other surface which it is desired to clean and the lever 28 is pressed with the fingers toward the hand grip 25. Through the medium of the arm 29, rod 30 and arm 24, rotation is thus im-
 10 parted to the gear 23 which, in turn, through the gear train 21, 19 and 18, rotates the fan at relatively high speed. Air is thus drawn into the fan housing through the opening 17 and the nozzle tube 12, as above explained, and the dust and dirt which is sucked or drawn up from the floor surface is directed through the housing in the rotation of the fan blades, and finally dis-
 15 charged through the nipple 14 into the collecting receptacle 15. In this manner, a relatively large floor surface may be easily and quickly cleaned. It will be understood that when pressure on the lever 28 is re-
 20 leased, the spring 31 immediately acts to re-
 25 turn said lever to its normal position and continue the rotation of the gear 23 so that there will be an uninterrupted and continuous rotation of the suction fan. The device is very light in weight and can be easily
 30 handled for the purpose of cleaning walls, draperies, or other articles. The size of the suction fan may, of course, be increased or decreased as desired, and the arrangement of the gearing for the actuation of this fan
 35 may likewise be changed in many ways which will readily suggest themselves to the mechanic for the purpose of obtaining a more compact arrangement or for driving the fan at a predetermined speed. The sev-
 40 eral other parts of the device as herein de-
 45 scribed are likewise susceptible of many modifications and it is accordingly to be un-
 derstood that while I have herein disclosed one practical embodiment of the device, the same may also be embodied in many alterna-
 50 tive forms. I, therefore, reserve the privilege of adopting all such changes in the general construction and arrangement of the several elements as may be fairly embodied within the spirit and scope of the invention as claimed.

I claim:—

1. A vacuum cleaner comprising, in combination, an elongated tubular member pro-
 55 vided with an induction nozzle at one end, a casing carried by said tubular member at one side thereof and in communication with the bore of said member, a shaft rotatably supported by the member and disposed therethrough, said shaft having one end portion extending within the casing and its opposite end portion beyond the side of the member remote from the casing, a suction fan within the casing and affixed to the por-
 60 tion of the shaft therein, means coacting
 65

with the opposite end portion of the shaft for rotating the same, and a collecting receptacle in connection with the interior of the casing.

2. A vacuum cleaner comprising, in com- 70 bination, an elongated tubular member pro-
 vided with an induction nozzle at one end, a casing carried by said tubular member at one side thereof and in communication with the bore of said member, a shaft rotatably 75 supported by the member and disposed therethrough, said shaft having one end portion extending within the casing and its opposite end portion beyond the side of the member remote from the casing, a suction 80 fan within the casing and affixed to the portion of the shaft therein, means coacting with the opposite end portion of the shaft for rotating the same, and a collecting receptacle in connection with the interior of 85 the casing, said receptacle being supported by both the casing and the member.

3. A vacuum cleaner comprising, in com- 90 bination, an elongated tubular member pro-
 vided with an induction nozzle at one end, a 95 casing carried by said tubular member at one side thereof and in communication with the bore of said member, a shaft rotatably supported by the member and disposed therethrough, said shaft having one end portion extending within the casing and its opposite end portion beyond the side of the member remote from the casing, a suction fan within the casing and affixed to the portion of the shaft therein, means coacting 100 with the opposite end portion of the shaft for rotating the same, and a collecting receptacle in connection with the interior of the casing, the means for rotating the shaft being manually operated and carried by the 105 member.

4. A vacuum cleaner comprising, in com- 110 bination, an elongated tubular member pro-
 vided with an induction nozzle at one end, a casing carried by said tubular member at one side thereof and in communication with the bore of said member, a shaft rotatably supported by the member and disposed therethrough, said shaft having one end portion extending within the casing and its opposite end portion beyond the side of the member remote from the casing, a suction fan within the casing and affixed to the portion of the shaft therein, means coacting 115 with the opposite end portion of the shaft for rotating the same, and a collecting receptacle in connection with the interior of the casing, the communication between the casing and the bore of the member being through the adjacent side wall of the mem- 120 ber.

5. In a vacuum cleaner, a pole, a fan housing mounted on one end of the pole, a handle forward upon the opposite end of said pole, a fan rotatably mounted in said 125

housing, a suction nozzle connected to the housing, a dust receiving receptacle, said housing having a discharge nipple opening into the receptacle, a casing mounted upon the pole, a gear train in said casing for rotating the fan, a lever pivotally mounted at one of its ends upon the pole, and extending adjacent said handle to be operated by the hand of the operator engaging said handle, an arm fixed to the lever pivot, means operatively connecting said arm to one ele-

ment of the gear train, and a spring operative to return the lever to its normal position and impart continuous rotation in one direction to the gear element.

15

In testimony whereof I hereunto affix my signature in the presence of two witnesses.

FLOYD L. LELAND.
